UNITED STATES PATENT OFFICE.

CHARLES RAW, OF TOLEDO, OHIO.

KNOCKDOWN BOX.

SPECIFICATION forming part of Letters Patent No. 673,963, dated May 14, 1901

Application filed November 15, 1900. Serial No. 36,551. (No model.)

To all whom it may concern:

Be it known that I, CHARLES RAW, a citizen of the United States, residing at Toledo, in the county of Lucas and State of Ohio, 5 have invented a new and useful Improvement in Knockdown Boxes, of which the following is a specification.

My invention relates to knockdown boxes, and has for its object to provide a box that 10 may be readily "knocked down" for return shipment, to occupy only the space required for the lumber composing it, and that may be readily assembled again for use as a box as often as knocked down; furthermore, to 15 provide a knockdown box that is strong and durable, inexpensive to manufacture, and that is secured by simple fastenings permanently attached to the box and always ready for use. I accomplish these objects as hereinafter described and illustrated in the drawings.

In the drawings, Figure 1 is an isometric view of my invention in the form of a crate-box fully set up. Fig. 2 is a similar view with the top removed and the rotatable latches 20 shown in open and closed position to illustrate the method of securing the sides and ends when set up as a box. Fig. 3 is a longitudinal section of the box set up complete, showing the method of securing the linked 25 wire hinges of the ends and the screw-clamp fastenings of the lid, also of latch-stops used in open boxes. Fig. 4 is a plan view of the 30 bottom, further illustrating the form and method of securing the linked wire hinges for the sides and ends and trussing the bottom. Fig. 5 is an isometric view of sides, ends, and 35 bottom in knockdown positions and showing manner of folding. Fig. 6 is an isometric view of a box constructed in accordance with 40 my invention as knocked down and fully secured for return shipment. Fig. 7 is an isometric view of a top-fastening. Fig. 8 is a similar view of a box increased in height, and Fig. 9 is a similar view of the same knocked 45 down and showing method of folding.

In the drawings, A is a box constructed in accordance with my invention, in which 1 designates the bottom of the box, which may be composed of one or more boards, having 5 its side edges mitered inward from the outer to the inner surface, and is provided with a plurality of transverse wires 2, secured to the

under side thereof at proper intervals, as required by the dimensions of the box, by staples 3, set astride the wire and driven into the 55 bottom and clenched on the upper side. Wires 2 are made longer than the width of the bottom and are secured thereto preferably with the end portions 4 and 5 projecting at unequal lengths beyond the side edges 60 of the bottom. Sides 6, having their bottom edges mitered to fit the mitered edges of the bottom, are provided, at intervals to align with the wires 2 of the bottom, with wires 7, having one end bent to form closed links 8 65 and the opposite end bent at a right angle to the edge of the link. Thus formed, wires 7 are secured to the outer surfaces of the sides 6 by driving the angled end as a nail into the side and by staples over the body 70 portion, with the outer end of each link 8 slightly projecting beyond the mitered edge of the side. The end portions 4 and 5, respectively, of wires 2 are then run through the links 8 of their respective sides and bent 75 back, as shown in Fig. 4, at angles to form the open links 9 and are then secured to the bottom in like manner as wires 7 are secured to the sides, thus hinging the sides 6 to the bottom 1, so that they will move on the hinges 80 thus formed from a folded position, as shown in Fig. 5, to a vertical position, as shown in Figs. 1 and 2, with their mitered edges abutting the mitered edges of the bottom. Each of the ends 10 of the box is also provided with 85 a plurality of wires 7, linked together in pairs by their links 8, one of each pair being secured to the inner surface transversely to the ends in like manner as they are secured to the sides. The free ends of the other wire 7 90 of each pair are then inserted through orifices 11, provided in the ends of the bottom and countersunk in the upper surface thereof until the links 8 are partly within the countersunk portions of the orifices 11, in which 95 position the projecting portions of the wires 7 are bent at the under surface, angled at the ends, and the angled ends driven into the bottom in the positions as shown in Fig. 4, whereby the ends 10 are hinged to the bottom, so that they will move from a folded horizontal position flat on the bottom to a vertical position, with their hinged edges abutting the bottom, as shown in Figs. 1 and 2. 100

The upper edges of ends 10 are longitudinally grooved to receive the wires 12, which are rotatably secured in the grooves by staples 3. Wires 12 are of a length to project beyond the sides 6, at the outer edges of which they are bent at right angles in the same plane and direction to form latches 13, as shown in Fig. 2, whereby when the sides and ends are in a vertical position to form a box, as in Figs. 1 and 2, the latches 13 may be turned downward to secure them in such position or turned upward to release them and allow them to be folded, as in Fig. 5.

The lid or cover 14 of the box A is provided with sides 15 and ends 16, together forming a projecting flange adapted to telescopically fit over the box when set up, as in Fig. 2. The lid 14 is provided with incuts 17 at the ends and with orifices 18 through the ends 16 below the incuts, and through orifices 18 are inserted from the lower side fasteners 19, which are threaded bolts having a flat head 20, projecting from one side only and adapted to engage suitable incuts 21 in the ends 10 of the box. The threaded end of fasteners 19 projects into the incuts 17 and is provided with horizontally-flanged cup-shaped washers 22, partially cut away at one side and adapted to fit into the incuts 17, with the horizontal flange resting on top of the cover 14 and forming a countersunk recess, into which the thumb-nuts 23 are run down on the threaded portions of fasteners 19 and are permanently secured thereon by forming rivet-heads on their threaded ends. Thus constructed, when the sides 6 and ends 10 are set up and latched and the cover is in position thereon, by inserting the heads 20 in the incuts 21 and running the thumb-nuts 23 down upon the washers 22 the cover will be compressed and firmly secured to the body of the box. When the box is knocked down, with the sides folded beneath the bottom and the ends on top of it, by fitting the cover down over the folded ends, turning the head 20 of the fastener 19 underneath the ends of the sides, and running the thumb-nuts down the parts are secured in a knockdown position for return shipment, as shown in Fig. 5. In boxes designed for use without a cover there is provided a stop 24, constructed of wire and secured to the upper corners of the sides 6, as shown in Fig. 3. These stops prevent the springing of the sides 10 outward far enough to release the latches 13 in handling the box.

It is apparent that as constructed in Figs. 1 and 2 the height of the box is limited to one-half the width of the bottom. In Figs. 8 and 9 are shown boxes constructed in accordance with my invention, wherein the height of the box is increased without increasing the width of the bottom. This is accomplished by providing a bottom in length slightly more than double the desired height of the box, ends 10 of the desired height, sides 6 of one-half the height of the ends 10, and additional sides 25, which have secured to them at inter-

vals on their inner faces a plurality of wires 7 in like manner as they are secured to sides 6, to which are linked the V-shaped wires 26, which are secured to the inner faces of sides 6, as described for the other fastenings, whereby the sides 25 are hinged to the sides 6, so that they will move from a folded position against the inner faces of sides 6 into 75 alignment therewith in the same plane, with their lower edges abutting the upper edges of sides 6. Thus constructed, sides 6 and 25 may be folded underneath the bottom, as shown in Fig. 9. For boxes so constructed ends 10, 80 in addition to the latch-wire 12, rotatably secured to the top edges thereof, are each also provided with an additional latch-wire 12, rotatably secured in grooves cut across the inner face of the ends at the height of the sides 85 6, and sides 25 are incut in their lower edges at opposite ends to form the open slots 27 when the sides are set up, through which the latches 13 of the lower wires 12 when raised to horizontal position will pass to allow the 90 setting up or knocking down of the sides. When set up as in Fig. 8, with the upper and lower latches 13 turned down, the sides 6 and 25 will be securely held in position. The lids or covers for boxes so constructed and the 95 means of fastening them are the same, as hereinbefore described, either in a set-up or knockdown position.

For chicken-crates I provide, as shown in Fig. 1, a top door 28, hinged in an opening 100 provided therefor at one end of the cover by the angled wire hinge 29. The door is held closed by one wing of the thumb-nut when run down to fasten the cover of the crate. The sides and ends of such crates are preferably 105 strengthened with the truss-wires 30 and bottoms constructed of more than one board, with truss-wires 31, which may be located at any desired intervals on the sides, ends, and bottom on the faces opposite to the hinge-wires.

In folding the sides the wires 7 of the sides 6 and 25 rest between the angles formed in the wires 2 and 26, whereby the sides and bottom are made to fold compactly together. 115

The lid when secured to the box either in a set-up or knockdown position forms a convenient means for handling the box, as well as securing it.

Having thus fully described my invention, 120 what I claim to be new, and desire to secure by Letters Patent, is—

1. In a knockdown box, a rectangular bottom having its side edges mitered, sides having their lower edges mitered to abut the mitered edges of the bottom, when the sides are in vertical position thereon, ends adapted to fit between the ends of the sides when the sides are in such vertical position, a plurality of hinges for each side and end, formed of 125 wires linked together, those for the sides being secured to the outer faces of the sides and bottom, and those for the ends to the inner face of the ends and through the bottom and 130

to its outer face, whereby the sides and ends are so hinged to the bottom that the sides may be folded outward and the ends inward from a vertical position, until they are respectively folded against opposite faces of the bottom, wire latches rotatably secured to the ends and adapted to be turned into or out of engagement with the sides, a cover having a depending flange, adapted to telescopically fit over the sides and ends, either when set up as a box or knocked down, and fasteners secured to the cover, adapted to secure the cover on the box, either as set up or knocked down.

2. In a knockdown box, the combination of the bottom 1 with the sides 6 and ends 10, hinged thereto by a plurality of wires 2 and 7, the sides to open outwardly and fold against the outer face, and the ends to fold inwardly against the inner face of the bottom, and the wires 12, rotatably secured to the ends, and having latches 13 formed thereon, adapted to engage the sides and secure the sides and ends set up as a box, when the latches are turned

down, and to release them for folding to a knockdown position, when turned up, substantially as shown and described.

3. In a knockdown box, the combination of the bottom 1, the sides 6 and 25, having incuts to form slots 27, and the ends 10, the sides 6 and the ends 10 being hinged to the bottom 1 by wires 2 and 7, and the sides 25 to the sides 6 by the wires 7 and 26, so that the sides 25 will fold inwardly against the inner faces of sides 6, and the sides 6 outwardly against the outer face of bottom 1, and the ends 10 inwardly against the upper face of the bottom 1, and a plurality of wires 12, each provided with latches 13 and rotatably secured to the ends 10, substantially as shown and described and for the purpose set forth.

In witness whereof I have hereunto set my hand this 12th day of November, A. D. 1900.

CHARLES RAW.
